A. FELDHEYM

MASSAGE INSTRUMENT

Filed July 25, 1923

INVENTOR
ALBERT FELDHEYM

BY ATT'y

Lincoln Johnson

UNITED STATES PATENT OFFICE.

ALBERT FELDHEYM, OF SAN FRANCISCO, CALIFORNIA.

MASSAGE INSTRUMENT.

Application filed July 25, 1923. Serial No. 653,684.

To all whom it may concern:

Be it known that I, ALBERT FELDHEYM, a citizen of the United States, and a resident of the city and county of San Francisco, 5 State of California, have made a new and useful invention—to wit, Improvements in a Massage Instrument; and I do hereby declare the following to be a full, clear, concise, and exact description of the same.

10 This invention relates particularly to a massaging apparatus having means thereon for electrically heating an applicator element and for equipping the applicator element with exposed terminals whereby electric current may be charged into any surface with which said terminals contact.

An object of the invention is to provide a applicator which may be detachably engaged with the threaded end of a motor 20 armature shaft, and which is provided with an electric heating coil therein for heating said applicator, and additionally provided with exposed terminals thereon through which a source of electric current may be 25 discharged into contact with any surface with which said terminals contact.

A further object of the invention is to provide a massaging instrument consisting of a motor having an armature shaft on 30 which an applicator may be mounted, and having means secured to said motor and connected to said applicator for electrically heating said applicator and charging the same with electricity. Other objects and advantages will appear as this description progresses.

In this specification and the annexed drawings, the invention is illustrated in the form considered to be the best, but it is to 40 be understood that the invention is not limited to such form, because it may be embodied in other forms, and it is also to be understood that in and by the claims following the description, it is desired to cover 45 the invention in whatsoever form it may be embodied.

In the accompanying one sheet of drawings,

Fig. 1 represents a side elevation of a 50 massaging instrument having an applicator attachment thereon constructed in accordance with my invention.

Fig. 2 is a side elevation of the massaging instrument shown in Fig. 1.

55 Fig. 3 is a view of the bottom side of the applicator element shown in Fig. 1.

Fig. 4 is a plan section taken through Fig. 1 on the line 4—4.

In detail, the construction illustrated in the drawings comprises an electric motor 1 having an armature 2 mounted on the shaft 3, the ends of which are revolubly journaled in said motor. The motor 1 has a handle 4 fixedly secured thereon to be used for holding said motor during its use, said handle also serving as a conduit for guiding the wires 5 carrying the electric current to the motor 1.

The end 6 of the armature shaft 3 projects beyond its bearing and is threaded exteriorly to permit an applicator 7 to be detachably engaged therewith. The armature shaft 6, either inside or outside of the motor, is provided with two pairs of contact rings 8, 9, 10, and 11 thereon, all of which are insulated from the said armature shaft. A bracket 12, formed of non-conducting material, is secured to the motor 1 for supporting a pair of points 13 and 14 in contact with the first pair of rings 8 and 9. 70

75 Lead wires 15 and 16 are connected to the respective points 13 and 14 for supplying current thereto. A pair of lead wires 17 and 18 are arranged within the armature shaft 3 and connected to the respective rings 8 and 9, said wires 17 and 18 being insulated from the said shaft. The applicator 7 is provided with a pair of lead wires 17' and 18' therein, which are adapted to contact with the wires 17 and 18 at the end where 80

85 said applicator 7 is attached to the armature shaft 3. The wires 17' and 18' are insulated from the material of which the applicator is formed, and said wires are connected to the opposite ends of the spirally wound, resistance wire, heating coil 19, insulated in the bottom portion of said applicator. Thus by supplying a source of 90

95 electric current to the coil 19, the same will become heated and the heat given off will be transmitted to the surrounding metal body of the applicator from which it will be transferred to the body of a patient, or any surface with which said applicator element contacts.

100 The applicator element 7 is formed in two halves to provide exposed terminals 20 and 21, which are spaced apart by the interposed insulating material 22. The terminals 20 and 21 and insulating material 22 are held 110 together by the headless non-conducting screws 23.

A bracket 24, formed of non-conducting material, is secured to the motor 1 and provided with a pair of points 25 and 26 thereon, which contact respectively with the 5 rings 10 and 11 on the armature shaft 3. Lead wires 27 and 28 supply electric current to and from the points 25 and 26, which said current is conveyed from the rings 8 and 9 by the insulated wires 29 and 30 to connection with each of the exposed terminals 20 and 21, forming the applicator element 7. The electric current used for running the 10 motor 1 and for heating the resistance coil 19 might also be used to charge the terminals 20 and 21 with electricity. However, I have shown an induction coil 32 mounted on the motor 1 to which the lead wires 27 and 28 are connected. The coil 32 is charged 15 with electricity from a battery 33 which is connected to said coil. The coil may thus be used to supply a small amount of electrical energy at high potential,—the usual regulatory means 34 on the coil, being provided for varying the potential.

20 Although I have shown and described a mechanism, for heating the applicator element and for charging the same with electricity, concealed within the motor housing, it is to be understood that it would be clearly 25 within the purview of the invention, to place said mechanism on the outside of the motor, or to form the same as a part of the

applicator element, and so construct it as to connect the same to a source of electrical energy. Thus a motor provided with an 35 applicator element thereon, constructed in the manner described, may be used very successfully for massaging and other electro-therapeutic treatments, as means are provided for administering in one operation, a 40 heated vibratory application, and at the same time charging with electricity the surface being vibrated.

Having thus described this invention, what I claim and desire to secure by Letters Pat- 45 ent is:

A device such as described, comprising a motor having an extended armature shaft; a source of electric current connected to said motor; an applicator detachably secured to 50 said shaft; means in said applicator connected to said source of electric current for heating said applicator; and exposed positive and negative terminals on said applicator connected to said source of electric 55 supply for passing faradic current to any surface with which said applicator terminals contact.

In testimony whereof, I have hereunto set my hand at San Francisco, California, this 60 5th day of July, 1923.

ALBERT FELDHEYM.
In presence of—
LINCOLN V. JOHNSON.
